Primary Examiner — Keli L Hill*Assistant Examiner* — Harold E Blackwell, II(74) *Attorney, Agent, or Firm* — Kirk A. Buhler; Buhler & Associates Patenting(57) **CLAIM**

The ornamental design for an adjustable travel pillow support, as shown and described.

DESCRIPTION

FIG. 1 is an articulated top left perspective view of an adjustable travel pillow support, showing my new design in its environment;

FIG. 2 is a left side elevation view thereof;

FIG. 3 is a right-side elevation view thereof;

FIG. 4 is a rear elevation view thereof;

FIG. 5 is a front elevation view thereof;

FIG. 6 is a top plan view thereof;

FIG. 7 is a bottom view thereof;

FIG. 8 is an articulated left perspective view thereof; and,

FIG. 9 is an articulated top left perspective view thereof.

The broken line showing of a travel pillow in FIG. 1 is included for the purpose of illustrating environment and forms no part of the claimed design.

1 Claim, 6 Drawing Sheets(56)
